[57] CLAIM

The ornamental design for a newspaper holder, as
shown and described.

DESCRIPTION

FIG. 1 is an environmental perspective view of a news-
paper holder showing my new design;

FIG. 2 is a front elevational view thereof;

FIG. 3 is a rear elevational view thereof;

FIG. 4 is a top view thereof;

FIG. 5 is a bottom view thereof;

FIG. 6 is a right side view thereof; and,

FIG. 7 is a left side view thereof;

The broken line showing of the window to which the
newspaper holder is attached as well as the open sign on
top of the newspaper holder is for illustrative purposes
only and forms no part of the claimed design.
